Specification for Design.

Patented Feb. 12, 1918.

Application filed November 24, 1917. Serial No. 203,849. Term of patent 14 years.

To all whom it may concern:

Be it known that I, JOEL C. WELLS, a citizen of the United States, residing at Southbridge, in the county of Worcester and State of Massachusetts, have invented a new and original ornamental Design for Lens-Clips, of which the following is a specification, reference being made to the accompanying drawings, forming a part thereof.

Figure I represents in dotted lines a lens provided with clips embodying my improved design.

Fig. II represents an enlarged front view

of my improved clip bringing out the several novel and ornamental portions of the design.

Fig. III represents a plan view thereof. I claim:

The ornamental design for a lens clip, substantially as illustrated.

In testimony whereof, I affix my signature in the presence of two witnesses.

JOEL C. WELLS.

Witnesses:

H. E. COLEMAN,
H. K. PARSONS.
